UNITED STATES PATENT OFFICE

WILLIAM SCOTT, OF MEDFORD, MASSACHUSETTS

VALVE

Application filed October 2, 1930. Serial No. 485,914.

The invention relates to valves and particularly to flushing valves for controlling the flow of water from a closet tank to the bowl for the purpose of flushing the latter.

5 In such apparatus a predetermined quantity of water normally is maintained in the tank and its admission thereto is controlled by a suitable ball cock. A flushing valve controls the discharge of water from the 10 tank to flush the bowl and refill the same. When the flushing valve is operated a portion of the water should pass through the bowl for flushing purposes and another portion should pass into the bowl and remain 15 there to assure a proper refill of the bowl. In the absence of some special provision for controlling the flow of water into the bowl, an effective resealing of the trap does not occur.

20 It is an object of the present invention to provide a flushing valve of simple construction adapted to control the flow of water from the tank to the bowl to assure the maintenance of a predetermined quantity of 25 refill water in the bowl.

It is another object of the invention to provide a flushing valve which operates automatically to retard the flow of water from the tank to the bowl at the end of the flushing 30 operation to permit a predetermined quantity of water to flow slowly into the bowl for refill purposes.

Before explaining in detail the present invention, it is to be understood that the invention is not limited in its application to the details of construction and arrangement 35 of parts illustrated in the accompanying drawings, since the invention is capable of other embodiments and of being practised or carried out in various ways. Also it is to be understood that the phraseology or terminology employed herein is for the purpose of description and not of limitation, and it 40 is not intended to limit the invention beyond the terms of the several claims hereto appended as considered in view of the prior art and the requirements thereof.

The invention will be more clearly understood from the following description in con-

junction with the accompanying drawings: in which,

Fig. 1 is a sectional elevational view of a tank having a discharge passage controlled by a flushing valve embodying the invention;

Figs. 2 and 3 are sectional elevational views of the flushing valve of the invention illustrating the relation of the parts during different positions in its operation; and

Fig. 4 is a sectional view taken upon the line 4—4 of Fig. 2.

In the accompanying drawings an apparatus is shown illustrating one embodiment of the invention and comprises a tank 10 adapted to contain a predetermined quantity of water 11. The water 11 is introduced through an inlet pipe 12 and its quantity is controlled by a suitable ball cock 13. A discharge pipe 15 connects the tank 10 with the bowl (not shown) of usual construction and is provided with a branch 16 to which an overflow pipe 17 is connected.

In accordance with the invention the flow of water through the discharge pipe 15 is controlled by a flushing valve 18 which is arranged to partially close the discharge pipe automatically when the water level in the tank has reached a predetermined level to permit a predetermined quantity of water to flow slowly from the tank to the bowl and then completely close the discharge pipe. The valve 18 may comprise a hollow float 20 having a rod 21 fixed therein and connected at its lower end to a disk 22 having a threaded boss 23 secured in a socket 24 on the end of a spindle 25. The upper end of the spindle 25 engages a disk 26 which holds a valve packing 27 against the bottom of the disk 22. The movement of the spindle 25 is guided by a sleeve 30 suspended by cross bars 31 within the discharge pipe 15. A disk or valve member 33 surrounds and is movably mounted upon the upper end portion of the spindle 25 and normally is supported by a shoulder 34 on the spindle 25. In this manner the valve members 27 and 33 are normally held in a predetermined spaced relation. The valve member 27 is adapted to cooperate with a valve seat 35 formed upon the top edge

of the discharge pipe 15 to completely close the same and the valve member 33 is adapted to be seated upon spaced lugs 36 extending inwardly from the inner wall of the discharge pipe 15 near the upper end thereof so as to provide a restricted annular passage 37 between the outer edge of the disk 33 and the inner surface of the discharge pipe 15.

5 A rod 40 is suitably secured to the upper 10 end of the rod 21 and is connected through the link 41 to one end of an operating lever 42 suitably pivoted in the usual manner for lifting the flushing valve 18. A pin 43 passing through the spindle 25 is adapted to 15 engage the lower end of the sleeve 30 and thereby limit the upward movement of the flushing valve 18.

Normally the valve member 27 engages the seat 35 to completely close the discharge pipe 20 15. The water level in the tank 10 under normal conditions is indicated by the dotted line *a* at which time the ball cock 13 is closed preventing the entrance of additional water into the tank through the inlet 12. When the 25 lever 42 is actuated to lift the float 20 the valve members 27 and 33 are raised from their respective seats, the former being carried by the float and the latter resting in spaced relation thereto upon the shoulder 34. 30 The valve members 27 and 33 are maintained in such raised position due to the buoyancy of the float 20. The water in the tank 10 then flows through the discharge pipe 15 and through the bowl (not shown) to flush the 35 same.

When the water level in the tank 10 has reached the point indicated by the dotted line *b* the float 20 has descended an amount such as to bring the disk valve member 33 into 40 engagement with the lugs 36 forming a seat therefor (Fig. 2), thus restricting the opening into the discharge pipe so that any further passage of water from the tank 10 to the bowl must pass through the annular passage 37. As a result, the flow of water into the bowl is greatly reduced and is insufficient to continue discharging action through the bowl. Consequently, this water collects in the bowl for refilling purposes and 45 continues to flow therein until the float 20 has descended to a point sufficient to bring the valve member 27 into engagement with its seat 35 and prevent further discharge of water from the tank.

55 I claim:

1. In a flushing valve fixture, a tank adapted to store a predetermined amount of water, an outlet pipe from said tank, a valve arranged to close said outlet first partially 60 and then completely, and means for controlling the closure of said valve in response to the water level in said tank.

2. In a flushing valve fixture, a tank adapted to store a predetermined amount of water, an outlet pipe from said tank having a valve

70 seat, a float within said tank, a valve member connected with said float adapted to cooperate with said seat to close said outlet pipe, and means controlled by the water level in said tank for partially closing said outlet pipe when the water level in the tank is lowered to a predetermined level.

75 3. In a flushing valve fixture, a tank adapted to store a predetermined amount of water, an outlet pipe from said tank having a valve seat, a float within said tank, a valve member connected with said float and adapted to cooperate with said seat to close said outlet pipe, and means for partially closing said outlet pipe when the water level in the tank is lowered to a predetermined level.

80 4. In a flushing valve fixture, a tank adapted to store a predetermined amount of water, an outlet pipe from said tank having a pair of valve seats, a pair of valve members 85 adapted to cooperate with said seats, one of said valve members being adapted to close said outlet partially and the other being adapted to close said outlet completely, and means for moving said valve members successively into engagement with their seats first to close said outlet partially and then completely.

85 90 5. In a flushing valve fixture, a tank adapted to store a predetermined amount of water, an outlet pipe from said tank having a valve seat, a float within said tank, an upper valve member carried by said float and adapted to cooperate with said seat to close said pipe, a spindle depending from said float and projecting into said pipe, a lug projecting from the inner wall of said pipe, a lower valve member movably carried by said spindle adapted to engage said lug to partially close said outlet pipe, and means for spacing said valve members a predetermined distance apart when out of engagement with said seat and lug.

95 100 105 6. In a flushing valve fixture, a tank adapted to store a predetermined amount of water, an outlet from said tank, a float within said tank having a depending spindle guided for movement in said pipe, a lower valve member movably mounted on said spindle and normally resting upon a shoulder thereon, and an upper valve member carried by said float between the same and said lower valve member, said lower valve member being adapted to close said outlet partially and said upper valve member being adapted to close said outlet completely.

110 In testimony whereof I affix my signature.
WILLIAM SCOTT.
